(57) **CLAIM**

The ornamental design for a vehicle debris catcher, as shown and described.

DESCRIPTION

FIG. 1 is a perspective view of a vehicle debris catcher;

FIG. 2 is a left side elevational view thereof;

FIG. 3 is a right side elevational view thereof;

FIG. 4 is a bottom plan view thereof;

FIG. 5 is a top plan view thereof;

FIG. 6 is a front elevational view thereof;

FIG. 7 is a rear elevational view thereof; and,

FIG. 8 is a perspective view thereof showing the vehicle debris catcher in use.

In the drawings, the broken lines in FIG. 8 depict a vehicle interior and form no part of the claimed design.
